CONSTANT AIR VOLUME DEVICE IN AIR CONDITIONING

BRIEF EXPLANATION OF DRAWINGS

The drawings show an example of the present invention, wherein FIG. 1 is a cross-sectional view of the center portion of a device in accordance with the present invention; FIG. 2 is the same cross-sectional view when air pressure is being received; FIG. 3 is an air pressure-speed diagram; FIG. 4 is a diagram for the load onto a conical spring and its deflection; FIGS. 5 and 6 are horizontal cross-sectional view and vertical cross-sectional view, respectively, showing the structure of the device; and FIGS. 7 and 8 are vertical sectional view and horizontal sectional view, respectively, showing an example for the application of the device.

DETAILED EXPLANATION OF THE PRESENT INVENTION

The present invention relates to a constant air volume device in air conditioning. In a control system of an ordinary type or of a damper type, the air volume exhausted out of each outlet varies depending on the changes in the pressure in the source of air, and also depending on the change in the pressure within ducts, and air is sent to a number of rooms through ducts diverging out of the source of air. When the air volume in any one of such rooms is adjusted, the air volume exhausted out of other rooms changes, therefore, it has been difficult to send air in the amount originally planned and designed to each room.

In view of the above, it is planned that a predetermined amount of air is constantly sent to each outlet through an automatic control even when the air pressure changes at the source of air and/or in the air supply duct, and moreover when the air volume needs to be changed later, it can be adjusted independently and freely. And at the same time the structure of the device can be quite simple and the device can be made at with a very low cost.

In conventional constant air volume devices, the constant air volume is set beforehand at a factory or even when it can be adjusted at the place where it is installed, the constant air volume can be adjusted at the place where it is installed, the constant air volume can be adjusted only within a small range. Contrary to this, in the device disclosed herein, the constant air volume can be adjusted with an almost entire range and further be a very simple method.

Next, the mechanism of the device shall be explained in reference to the drawings.

In FIG. 1 and FIG. 2, a conical spring is shown by 1, and 2 is an air pressure plate attached to its wider diameter end 1', wherein an axle 4 is inserted through an axle hole 3, which is bored at the center of the air pressure plate 2, and through a narrower diameter end 1'' of the conical spring 1. And 5 is a supporting bar provided in a casing 6, and an end of said axle 4 protruding out of the smaller diameter end 1'' of the conical spring is fixed to the center of said supporting bar with a nut 7. In the drawings an arrow F shows the direction of the air blowing in.

The conical spring 1 will have such deflection L with a parabolic curve a shown in FIG. 4 against the load R working on the air pressure plate 2. And at the same time, a cross-sectional area A of the air passage within the casing (when the air pressure plate is round, the cross-sectional area is obtained by: Diameter of the round $\times$ $\pi \times L$) will vary accordingly. FIG. 1 shows the deflection L₁ against the load R₁, and FIG. 2 shows the deflection L₂ against the load R₂.

Generally speaking, the volume of flow of air Q can be obtained by the following formula:

$$Q = C \times A \times V$$

An since V is in proportion to $\sqrt{\Delta P}$ as shown in FIG. 3

$A = C \times A \times \sqrt{\Delta P}$, wherein V represents the speed of flow of air and C shows a coefficient (C has an almost constant value).

Therefore, the condition for always maintaining Q in a constant value regardless of change in the value of P, will be having A change in proportion to $\frac{1}{\sqrt{P}}$. Thus, it is necessary to have 1 change in proportion to $\frac{1}{\sqrt{P}}$. This can be quite easily done by using the conical spring mentioned above.

Thus, it can be made possible to always discharge air in a constant volume out of an outlet by an automatic control even when the air pressure P within the source of air and/or the air supply duct changes.

In a central duct system with one source of air, the device can be installed at an appropriate position in the duct or near the outlet, or within a sterilizing box having blowout outlets, regardless of the air passage lay out, and it can be directly connected to an air conditioner. At the same time, when air flows towards the outlet along the external surface of the conical spring which is pressed down as air pressure is given, the resistance is small and the volume of sound by flow of air is also small.

Furthermore the device has such advantages that the structure and manufacture of the same will be very simple compared to conventional devices, and can be obtained with a very low cost, through the use of the conical spring.

The conical spring in the present invention is not limited to such spring as being wound in a conical shape, but it can be of such type that the diameter is gradually reduced from the wider diameter end towards the narrower diameter end and it does not have to have a certain cross-sectional shape.

Now a concrete explanation will be given based on an example shown on the drawings.

Example

The control device for constant air volume which is adjustable as shown in FIG. 5 and FIG. 6 consists of an outer casing 10, inner casing 11, a conical spring 12 and an air pressure plate 13 as its main components. Each of the inner casing 11 and outer casing 10 has slits 14 arranged in a circumferential direction with uniform intervals, and the area of the opening varies depending on the position where the both casings overlap. The θ shown in FIG. 5 represents the degree of opening of the slit 14.

The inner casing 11 is fixed to a frame 15. An the degree of opening of the slits 14 is adjusted by rotating the outer casing 10 with an opening degree control handle 17 attached to one end of a central axle 16 which extends through the inner casing and at its other end is fixed to the outer casing 10 located around the inner casing 11.

Therefore the air is, as shown in FIG. 6, first blown against the air pressure plate 13, then is diverged to the circumference and is sent into the inner casing 11 through the slit openings 14 of the inner and outer casings, then is discharged to outside.

In this case the spring 12 of the air pressure plate 13 expands and contracts mainly due to the difference in the air pressure between the upstream and the down stream air flow, and the rate of such expansion and contraction is arranged so that it corresponds to the relationship between the air pressure difference and the speed of the upstream air passing through the opening. Thus, even when the air pressure changes, the area of the opening through which air passes is adjusted in an axial direction accordingly, thereby the volume of air sent downstream is maintained constant.

That is, the volume of air is kept constant according to the width of the opening which changes depending on the degree of overlapping of the slits 14 in the inner and outer casings. Therefore, the constant volume of air can be adjusted by changing the width of the slit opening with the rotation of the central axle 16.

Such an adjustment can be done by remote control, and when a calibration is made having a degree of rotation of the

axle and a volume of air corresponding to each other, the volume of air which needs to be kept constant can be precisely established by the air volume calibration. A supporting bar 18 is used to secure the lower end of the axle 16.

FIG. 7 and FIG. 8 show an application example of the above mentioned control devices for constant air volume which is adjustable. These drawings shown a case where three of such adjustable control devices for constant air volume as shown in FIG. 5 and FIG. 6 are installed in a duct 20.

I claim:

1. A constant air volume device for use in air-conditioning apparatus and the like comprising a tubular wall section forming the upstream portion of an axially extending air flow passageway having an inlet at one end thereof, wall means secured to said tubular wall section spaced axially from the inlet end thereof and forming a downstream continuation of the air flow passageway having a smaller cross-sectional area than and in alignment with the portion of said air flow passageway formed by said tubular section, a support bar attached to and extending transversely across said wall means forming the downstream continuation of the air flow passageway at a location spaced axially downstream from the upstream and of said wall means, a shaft member extending axially through the air flow passageway from said tubular wall section into said wall means and secured at its downstream end to said support bar, a conically shaped spring member disposed within and extending in the direction of air flow within the air flow passageway and having its larger diameter end located in the upstream end of the air flow passageway formed by said tubular wall section, said spring member disposed concentrically about said shaft, the smaller diameter downstream end of said spring member secured in a stationary position to said support bar within the downstream continuation of the air flow passageway, said spring member is free to contract and expand in the axial direction of the air flow passageway, a pressure plate attached to the upstream end of said spring member and extending transversely of the direction of air flow within the passageway and having a centrally disposed opening through which said shaft member extends so that said pressure plate is displaceable with said spring member in sliding relationship with said shaft member, said pressure plate having a diametrical dimension approximately equal to the inside diameter of the downstream section of the air flow passageway, said pressure plate and said wall means combined to form a variable air flow opening at the inlet to the downstream section of the air flow passageway and said spring member is calibrated to contract and expand in response to the air pressure acting on said pressure plate so

that the axially extending cross sectional area of the variable air flow opening is adjusted on a parabolic curve for regulating the volume of air passing through the device.

2. A constant air volume device, as set forth in claim 1, wherein said tubular wall section has a first diameter, said wall means comprise an annular shaped frame means secured to the inner surface of said tubular member downstream from the inlet thereto and extending radially inwardly therefrom and then axially in the downstream direction of the air flow 5 10 15 20 25 30 35 40 45 passageway forming the downstream continuation of the flow passageway and the downstream continuation has a second diameter which is smaller than the first diameter of said tubular member, and inner casing extending in the axial direction of said tubular member and secured at its downstream end to said frame means within the downstream continuation of the air flow passageway and extending therefrom in the upstream direction through said tubular member and terminating at a position spaced downstream from the inlet to said tubular member, said support bar secured to and extending transversely across said frame adjacent and downstream from the downstream end of said inner casing, said shaft member is centrally disposed within said inner casing, the upstream end of said shaft is located upstream from the upstream end of said inner casing, and an outer casing concentrically mounted on the upstream end of said shaft and positioned in closely spaced relationship exteriorly about said inner casing, said conically shaped spring member disposed concentrically about said shaft is located within said inner casing, said pressure plate which is slidably mounted about said shaft is secured to the larger diameter upstream end of said spring member extending transversely of and located within said inner casing, said outer casing having a transverse surface extending across said tubular member upstream from the upstream end of said inner casing and having openings therethrough for admitting air flow to the upstream surface of said pressure plate within said inner casing, said inner casing has at least one axially extending slit formed in its circumferential periphery, said outer casing has at least one axially extending slit formed in its circumferential periphery and arranged for registering with the slit in said inner casing, said shaft is rotatably mounted in said support bar for rotating said outer casing relative to said inner casing for varying the registration of said slits in said inner and outer casing and establishing the extent of the angular opening of the slits, and said spring member and pressure plate are axially displaceable along said shaft within said inner casing for varying the axial length of the openings of the slits, and means for rotatably positioning said shaft.
